UNITED STATES PATENT OFFICE

2,006,395

ELECTRIC FLASHER

William Huppert, New York, N. Y., assignor to
Ampex, Inc., New York, N. Y., a corporation of
New York

Application October 12, 1932, Serial No. 637,395

1 Claim. (Cl. 200—115.5)

This invention relates to electric flashers, for interrupting electric circuits to intermittently flash lights or operate motors.

An object of this invention is to provide a device of the character described in the form of a combination plug and socket fitting having highly improved means for mounting the current carrying portions and thermostatic elements on a single wall of the flasher, the parts being furthermore compactly arranged within a housing to permit an easy assembling.

A further object of this invention is to provide a compact and rugged device of the character described, which shall be comparatively cheap of manufacture, easy to assemble, and practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawing, in which is shown one of the various possible embodiments of this invention,

Fig. 1 is a perspective view of a device embodying the invention;

Fig. 2 is an axial sectional view of the device shown in Fig. 1;

Fig. 3 is a cross-sectional view taken on line 3—3 of Fig. 2; and

Fig. 4 is an axial, sectional view of a device embodying the invention and illustrating a modified construction.

Referring now in detail to the drawing, and particularly to Figs. 1, 2 and 3 thereof, 10 designates a flasher device embodying the invention, here shown for the purpose of illustration only, in the form of a combination plug and socket fitting.

The device 10 comprises a shell 11 having a cylindrical outer metallic portion 12 formed with inwardly extending rim flanges 14 and 15 at the opposite ends thereof. Seated on the lower flange 15 is a circular disc 16 of insulating material, preferably formed with a shoulder 17 for receiving the flange 15. The disc 16 may be formed with a pair of parallel slots 18 for receiving the usual plug blades of another fitting. Contacting the other flange 14 is a disc 19 likewise made of insulating material and disposed within the cylindrical shell 12; and between the discs 16 and 19 is a cylindrical lining member

20 made of any suitable insulating material and adapted to contact and retain the discs seated on and in contact with the rim flanges 14 and 15, respectively.

The disc 19 may likewise be provided with plug blade receiving slots 22 aligned with the slots 18 of the lower disc. Mounted on said disc 19 is a plug blade 24 extending through one of the openings 22 and having a foot portion 25 extending outwardly and contacting the inner surface of said disc 19. Attached to said foot portion 25 is a spring contact member or blade 26 fixed to said foot portion by means of a rivet 27, a metallic washer 28 being interposed between said blade 26 and said foot portion. It will be noted that the rivet 27 extends through the disc 19 and serves to attach together the blades 24 and 26 and mount the same on said disc.

A second plug blade 30, similar to blade 24 and symmetrically disposed with respect thereto, may likewise be mounted on the disc 19 and extends through the other slot 22 therein. The blade 30 likewise has a foot portion 31 disposed within the housing and attached to the disc by means of an eyelet or rivet 33. The foot portion 31, however, is insulated from the rivet 33 by means of a small bushing 34 made of insulating material having a tubular portion extending through an opening within said foot portion. There is also attached to said foot portion 31 an L-shaped contact blade 35 lying against the inner surface of the disc, which is recessed for partially receiving the same; said blade 35 being insulated from the rivet 33 but contacting said foot portion 31. It will be noted that said blade 35 is provided with a portion 36 parallel to a plane through the blades 24 and 30, the outer end of said portion 36 being spaced from the blade 24. The rivet 33, further serves to attach to the disc 19 a thermostatic unit comprising a bi-metallic thermostatic blade 37 likewise of L-shape and superimposing the blade 35. The blade 37, however, is parallel to and spaced from the blade 35 and is insulated therefrom by means of the bushing 34.

Mounted on said blade 37 is an asbestos sleeve 38 carrying a thin heating wire 39 attached at one end 40 thereof to the blade 35 and at the other end 41 thereof to said blade 37. The rivet 33 further serves to attach a spring contact blade 44, similar to the blade 26, to the thermostatic blade 37. The blade 44 is thus insulated from the blades 35 and 30. The blades 35 and 37 are provided with contact points 46 and 47, respectively, at the free ends thereof.

The operation of the device will now be under-

stood. Current entering the blade 30 will pass to the blade 35 and then through the wire 39 to the blade 37 and thence to the spring contact blade 44. The wire 39 will then be heated for causing the free end of the blade 37 to bend for causing the contact point 41 to engage the contact point 46. The current will then be short circuited from the heating coil 39 to permit the same to cool and permit the blade 37 to move out of contact with respect to the blade 35. The operation is then repeated continuously. The current passes directly through the blade 24 to the blade 26. It will be noted that the rivet 33 serves to mount the blades 30 and 35, as well as the blade 37 and the spring contact blade 44 to the disc 19 with the blades 37 and 44 insulated from the blades 30 and 35 except through the heating wire. Thus all of the current carrying parts are mounted on the disc 19 and may be assembled therewith separately and then incorporated into the shell.

In Fig. 4 of the drawing, there is shown a modified construction wherein the shell 50 comprises a portion 51 made of insulating material such as a phenol-condensate product, having a bottom wall 52 and a cylindrical wall 53. The open end of the wall 53 is formed with a shoulder 54 receiving an insulating disc 55. The end wall 52 is formed with a pair of parallel slots 58 for receiving plug blades from another fitting. The disc 55 is seated on the shoulder 54 and may be attached to the shell 51 by means of a screw 60 having a head 61 disposed within a countersunk opening in the end wall 52 and having a screw threaded end portion 62 engaging the threads within a screw threaded opening in said disc. Said disc 55 is likewise formed with parallel slots 63 aligned with slots 58.

The blades and thermostatic unit shown in Fig. 2 of the drawing may be mounted on the disc

55 the same as they are mounted on the disc 19, as illustrated in said Fig. 2.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter 10 herein set forth or shown in the accompanying drawing is to be interpreted as illustrative and not in a limiting sense.

Having thus described my invention, I claim as new and desire to secure by Letters Patent:

A flasher device for electric circuits comprising a shell made of insulating material and having a bottom wall and an annular wall extending from said bottom wall, the edge of said annular wall being formed with an internal shoulder, a disc closing the open end of said shell and contacting said internal shoulder, a screw extending through said bottom wall and having an outer end thereof screwed to said disc, a pair of substantially similar, symmetrically disposed blades attached to said disc and adapted to be contacted by blades of another fitting, a contact blade within said shell in electrical contact with one of said pair of blades, a cooperating thermostat blade in said shell insulated from said one of said pair of blades and from said contact blade, a heating coil on said thermostat blade, one end of which is connected to the thermostat blade and the other end of which is attached to said contact blade, said contact blade, thermostat 35 blade and one of said pair of blades being fastened to said disc by a single fastening device.

WILLIAM HUPPERT.
